UNITED STATES PATENT OFFICE.

IRA E. SARBER, OF ELMORE, ALABAMA.

BURIAL-VAULT LID.

Application filed October 19, 1926. Serial No. 142,676.

This invention relates to a burial vault lid and it is an object of the invention to provide a device of this kind formed from reinforced cementitious material and which provides a flat and highly polished top surface in simulation of a marble or stone slab.

It is also an object of the invention to provide a lid of this kind provided with depending marginal flanges, certain of said flanges being provided adjacent to their extremities with outstanding and laterally directed lift members to facilitate handling thereof.

An additional object of the invention is to provide a lid of this kind formed of cementitious material having its outer top surface highly polished and with its top marginal edges beveled to increase the esthetic value of the lid.

The invention consists in the details of construction and in the combination and arrangement of the several parts of my improved burial vault lid whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view in perspective of a burial vault lid constructed in accordance with an embodiment of my invention and in applied position, the coacting vault being shown in fragment;

Figure 2 is a vertical sectional view taken transversely of the lid as illustrated in Figure 1 with the coacting vault in fragment;

Figure 3 is a view in top plan of my improved lid showing in full lines the reinforcement and the outstanding lateral lifts with the outlines of the lid indicated by broken lines;

Figure 4 is a view in perspective illustrating a reinforcement for an end portion of the lid and the lifts associated therewith;

Figure 5 is a transverse sectional view taken through a lid illustrating a slightly modified design.

As disclosed in Figures 1 to 3 inclusive, my improved lid L comprises a body por-

tion 1 of requisite dimensions having its outer top surface level or flat and highly polished, the marginal edges of said surface being beveled, as at 2, whereby is produced an effective simulation of a marble or stone slab. This effect is further enhanced by having the marginal portion of the body 1 projecting a slight distance beyond the depending flanges 3 arranged preferably about three quarters of an inch inwardly of the marginal face of the body 1.

In practice, I find it of advantage to have the body 1 about three inches in thickness with the flanges 3 about five inches long and about one end one-half inches thick.

The body 1 together with the flanges 3 provide a lid or cover of a box type which is adapted to be telescopically engaged over the upper portion of the vault V. As illustrated in Figures 1 and 2, the walls of such vault are also preferably made of cementitious material.

The body 1 and flanges 3 of the lid L have embedded therein a reinforcement R comprising parallel rods 4 extending lengthwise of the body 1 and of the flanges 3, said rods 4 being connected by the transversely disposed rods 5 which extend downwardly as at 5^a, within the side flanges 3 of the lid or cover L. The rods 4 and 5 at their overlying portions may be welded or otherwise attached one to the other so that the reinforcement R will constitute substantially a unitary structure.

Each end flange 3 of the lid L also has embedded therein a reinforcing rod 6 arranged adjacent to the lower portion thereof and which has its extremities continued by the extensions 7 extending within the adjacent portions of the side flanges 3 whereby each end portion of the lid or cover L is further strengthened by a substantially U-shaped reinforcing member.

Adjacent to each end and in relatively close proximity to its outer longitudinal margin, each side flange 3 has extending outwardly therefrom a lift or loop member 8 formed at the central portion of a rod, said rod being continued beyond opposite sides of the lift or loop member 8 by the arms 9 terminating in upstanding extensions 10. The arms 9 and the extensions 10 are embedded within a side flange 3 and the upstanding extensions 10 are disposed rearwardly of and in close proximity to an ex-

tension 7 of the reinforcing rod 6 whereby the lift or member 8 is effectively maintained in applied position.

The construction of the lid or cover illustrated in Figure 5 is substantially the same as that hereinbefore set forth except that the outer faces of the side flanges 3' are flush with the marginal edges of the body 1'.

It is to be understood that in practice the 10 vault may be placed within the ground at a depth whereby the upper portion of the applied lid or cover L will extend slightly above the ground surface and, if desired, a marble or granite slab may be placed directly thereon although the finish of the top surface does not make this necessary. It is also to be understood that a scroll if desired may be properly arranged upon the applied lid or cover L.

20 My improved lid or cover is of particular benefit to the person of average means who is enabled to obtain an effective substitute for a marble or other stone slab at a comparatively low cost.

25 In the making of the lid or cover L the top surface may be pure white or colored as desired.

From the foregoing description it is thought to be obvious that a burial vault lid 30 constructed in accordance with my invention is particularly well adapted for use by reason of the convenience and facility with which it may be assembled and used, and it

will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A lifting handle adapted to be used upon the lid of a burial vault comprising a 45 length or rod coiled at a point midway between its ends in the form of a loop, said rod having end portions lying in the same plane and upstanding extremities disposed parallel with relation to each other and lying in a plane approximately at a right angle to the plane of the coil.

2. A lifting handle adapted to be used upon the lid of a burial vault comprising a 55 length of rod coiled at a point between its ends in the form of a loop, said rod having end portions lying in the same plane and upstanding extremities disposed parallel with relation to each other and lying in a plane approximately at a right angle to the plane of the coil, both of said extremities being disposed beyond the same side of the plane of the coil.

In testimony whereof I hereunto affix my signature.

IRA E. SARBER.
